(21) Appl. No.: **29/241,232**

CLAIM

(22) Filed: **Oct. 26, 2005**

The ornamental design for a small belt-pack air compressor for ink pens, as shown and described.

(51) LOC (8) Cl. **15-02**

DESCRIPTION

(52) U.S. Cl. **D15/7**

FIG. 1 is a perspective view of a small belt-pack air compressor for ink pens;

(58) Field of Classification Search D15/7-9;

FIG. 2 is a front view thereof;

D23/232, 231; 417/359, 415-416, 410,1,

417/321, 265, 405

See application file for complete search history.

FIG. 4 is a left side view thereof;

FIG. 5 is a right side view thereof;

FIG. 6 is a top view thereof;

FIG. 7 is a bottom view thereof; and,

FIG. 8 is an embodiment view thereof.

It being understood that the broken lines are for illustrative purposes only and form no part of the claimed design.
